United States Patent Office

Des. 177,160
Patented Mar. 13, 1956

177,160

PENCIL HOLDER

William F. Vernon, Newton, Iowa, assignor to The Vernon Company, Newton, Iowa, a corporation of Iowa

Application August 1, 1955, Serial No. 37,256

Term of patent 7 years

(Cl. D74—21)

Fig. 1

Fig. 2

Fig. 3

Figures 3 and 4 are respectively top and bottom plan views thereof.

The broken line illustration of a pencil as shown in Figure 2 is for illustrative purposes only.

I claim:

The ornamental design for a pencil holder, substantially as shown and described.
